UNITED STATES PATENT OFFICE.

RICHARD W. HIMMELBERGER, OF LEBANON, PENNSYLVANIA.

RECEPTACLE.

1,272,443.

Specification of Letters Patent. Patented July 16, 1918.

Application filed September 9, 1916. Serial No. 119,292.

To all whom it may concern:

Be it known that I, RICHARD W. HIMMELBERGER, a citizen of the United States, residing at Lebanon, in the county of Lebanon and State of Pennsylvania, have invented 5 certain new and useful Improvements in Receptacles, of which the following is a specification.

This invention relates to certain new and 10 useful improvements in receptacles.

The primary object of the invention resides in the provision of a receptacle provided with a rotary valve plate which may be readily locked in horizontal or closed position to 15 close the lower portion of the receptacle.

Another object of the invention resides in the provision of a receptacle of this character in which the valve plate for preventing the escape of offensive odors from the 20 receptacle, may be of simple construction and operation and controlled by a handle on the side of the receptacle.

For a further object, the invention contemplates the provision of a receptacle and 25 valve of this character which will be inexpensive as well as highly efficient in use.

With these and other objects in view, as 30 will appear as the nature of the invention is better understood, the same consists in the novel combination and arrangement of parts hereinafter more fully described, illustrated in the accompanying drawings and pointed out in the appended claims.

In the accompanying drawings forming 35 a part of this application and in which like designating characters refer to corresponding parts throughout the several views,

Figure 1 is a longitudinal section through the complete device with the valve plate in 40 closed position, and locked, the plate and locking means being indicated by dotted lines in open position.

Fig. 2 is an elevation of the complete device with the valve plate locked in closed 45 position but with the handle extending upwardly.

Fig. 3 is a detail enlarged perspective of the valve plate and handle, and

Fig. 4 is a detail enlarged perspective of 50 the locking disk mounted upon the handle.

Referring more in detail to the drawings, 1 designates the receptacle, 2 the bail handle and 3 the cover of the same, the receptacle being of conventional form.

55 Positioned in the receptacle 1, a suitable distance above the bottom of the same is a

valve plate 4 which is mounted upon a supporting stem 5 which extends through one side of the receptacle body and is turned to form a handle 6. The opposite end of the 60 stem 5 is rotatably mounted in the opposite sides of the receptacle body as shown at 7. A disinfectant or other liquid 8 is placed in the receptacle 1 below the valve plate 4 and the said valve plate 4 is preferably of 65 a form to correspond with the interior of the receptacle.

In order to lock the valve plate 4 in its normal or closed position, I have provided a locking disk 9 upon the extended end of 70 the stem 5 with a plurality of notches 10 formed in its periphery. To coöperate with the locking plate 9, I have also provided a pivoted locking member 11 which has one end mounted upon the pin 12 extended 75 through the ears 13 formed on the side of the receptacle 1 above the stem 5. The pivoted member 11 is curved downwardly around one side of the locking disk 9 and has its free lower end 14 bent upwardly. 80 for engagement in one of the notches 10.

From the foregoing it will be evident that all matter deposited in the receptacle 1 will rest upon the valve plate 4 until the pivoted locking member 11 is released from the locking disk 9, when the weight of the material upon the valve plate 4 will cause the same to swing within the receptacle 1 and permit the material to drop into the liquid 8. The valve plate 4 will then automatically return 90 to its normal or closed position, with the part 6 extending downwardly owing to the plate being mounted centrally upon the stem 5.

It will be evident that the pivoted locking member 11 will also automatically return to vertical position, the end 14 thereof engaging in the proper notch 10.

In order to assure automatic closing and locking of the valve plate 4, I have provided a knob 15 upon the free end of the handle 6 which will also serve as a weight, causing the handle 6 to swing downwardly when the locking plate 9 is released. It will be understood that the handle 6 is normally extended downwardly, as shown in full lines in Fig. 1 of the drawings. It will furthermore be understood that when the valve plate 4 is in closed position, offensive odors from the material beneath the 105 same cannot escape from the receptacle 1.

While the form of the invention shown

and described is what is believed to be the preferred embodiment thereof, it is nevertheless to be understood that minor changes may be made therein without departing 5 from the spirit and scope of the invention as claimed.

What is claimed as new is:

1. The combination with a receptacle of a rotatable valve plate mounted therein a 10 notched disk fixed to rotate with the valve plate, and a pivoted latch member adapted for engagement with one of the notches to normally retain the plate in a horizontal position.
- 15 2. The combination with a receptacle and a valve plate rotatably mounted therein, a notched disk fixed to rotate with the valve plate, a latch member pivotally mounted on the receptacle and movable in a direction at 20 right angles to the plane of rotation of the valve plate and adapted to be engaged in one of the notches to retain the valve plate in a horizontal position.
- 25 3. The combination with a receptacle having a rotatable valve plate mounted therein and normally arranged in a horizontal position, a locking plate fixed to rotate with the valve, and a pivoted locking member adapted for engagement with the locking plate 30 to retain the valve in a horizontal position.
- 35 4. The combination with a receptacle, of a valve plate rotatably mounted therein, a notched locking disk fixed to rotate with the

valve plate, a latch member pivotally mounted 35 on the receptacle and movable in a vertical plane, the latch member being longitudinally curved and having an upturned end adapted for engagement with one of the notches to retain the valve plate in a horizontal position.

5. A container of the character described comprising a receptacle, a valve plate rotatably mounted therein and normally retained in a horizontal position, a notched disk fixed to rotate with the valve plate, a pivoted latch 45 member adapted for engagement with one of the notches in the plate to retain the same in a horizontal position, and means for returning the valve plate to its normal position.

6. A valved receptacle comprising a receptacle proper adapted to contain a liquid, a rotary stem mounted in said receptacle above the liquid, a valve plate carried by said stem, a handle formed upon one end of said stem, a locking disk mounted upon said end of the stem, and a pivoted locking member 50 normally engaged with said locking member to prevent rotation of said stem and said valve plate.

In testimony whereof I affix my signature 60 in presence of two witnesses.

RICHARD W. HIMMELBERGER.
